AIR BRAKE BLEEDER

Ewell Fletcher Wideman, Wetumpka, Ala.

Application May 19, 1949, Serial No. 94,190

6 Claims. (Cl. 303—80)

1
This invention relates to new and useful improvements and structural refinements in mechanisms for bleeding air brakes on railroad cars, and the principal objects of the invention is to greatly expedite the performance of the bleeding operation.

Air brake systems on railroad cars are, of course, provided with normally closed bleeder valves which may be individually opened by the manipulation of a lever provided on each car, but since each valve must be manually closed after bleeding, the operation of bleeding several cars consumes considerable time, not only of the person who performs the actual operation, but of the engine crew, switchmen, etc., who cannot proceed with their respective duties until after the bleeding operation is completed.

It is, therefore, the principal object of the invention to expedite the bleeding operation as aforesaid, this being achieved by the provision of a bleeding mechanism which maintains the bleeder valve in an open position until the bleeding operation is completed, and then automatically causes the valve to be closed.

An important feature of the invention resides in the provision of automatic means for causing the bleeder valve to close, these means being responsive to movements of the car on which the apparatus is installed, so that when the brakes are locked the brake system may be bled and the brakes released by a simple actuation of the lever, whereupon movements of the car, such as for example, when "jerking," actuates the mechanism so as to automatically close the bleeder valve.

Some of the advantages of the invention reside in its simplicity of construction, and in its adaptability to installation on conventional as well as new railroad equipment.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention;
Figure 2 is an elevational view thereof as it appears when the bleeder valve is closed;

Figure 3 is an elevational view, similar to that shown in Figure 2, but illustrating the apparatus in the bleeding position;

Figure 4 is a cross-sectional detail, taken substantially in the plane of the line 4—4 in Figure 2, and

2
Figure 5 is an elevational view of one of the release actuating elements used in the invention.

Like characters of reference are employed to designate like parts in the specification and throughout the several views.

Referring now to the accompanying drawings in detail, the invention consists of an air brake bleeding mechanism designated generally by the reference character 10, this being intended, of course, for use on railroad cars and embodying in its construction an inverted U-shaped member 12 which is adapted for attachment in a transverse position to the bottom 14 of a railroad car, as will be clearly apparent.

The free end portions of the member 12 are provided with transversely aligned slots 16 to slidably receive flattened end portions 18 of a control rod 20, and if desired, the member 12 may be formed in two complementary sections connected together as at 22, so as to facilitate installation of the rod 20 therein.

The control rod 20 is connected in a conventional manner to a brake bleeder valve 82, such as for example, by providing the rod with a slot 19 to operatively receive the actuating lever 83 of a conventional bleeder valve 82 on a compressed air tank 84. Accordingly, when the rod is pulled from a central position in either direction, the bleeder valve is opened, while sliding the control rod back to its central position causes the valve to close. The central position of the control rod is illustrated in Figures 1 and 2.

To facilitate sliding of the rod 20, the end portions 18 thereof are usually provided with suitable manipulating handles 24 which are slidable in suitable brackets 26 attached to both sides of the car, it being understood that this arrangement is conventional and does not constitute a component of the instant invention.

The invention involves the provision of a locking arm 28 which is pivotally attached at one end thereof as at 30 to an upstanding bracket 32 secured to one of the control rod portions 18, the arm 28 being provided intermediate its ends with a pair of notches 34, 36 while the remaining end thereof carries what may be generally referred as a lifting member 38.

This member simply consists of a pair of downwardly divergent brackets 40 which are secured at their upper ends to the arm 28 while their lower extremities are provided with outwardly angulated flanges 42 secured, in turn, to intermediate portions of a pair of spaced parallel bars 44. These bars are disposed below and at the sides

of the control rod 20, and it will be apparent from the foregoing that by virtue of the pivotal connection 30, the arm 28 together with the member 38 may drop from its substantially horizontal position as shown in Figures 1 and 2 to a lowered position as shown in Figure 3, this dropping action occurring when either of the aforementioned notches 34, 36 enters a slot 46 in a bracket 48 through which the arm 28 is slidably. The bracket 48 is secured to the aforementioned member 12 and the arm 28, which is slidable with the rod 20, slides through the slot 46 into bracket 48, so that when the rod 20 is slid in either direction from its central position, one of the notches 34, 36 will eventually enter the slot 46 and dropping of the arm 28 together with the member 38 will be effected, as shown in Figure 3.

The control rod 20 itself is slidable through the bracket 48 as well as through a similar, second bracket 50, the latter also being secured to the member 12, and both the bracket 48 and the bracket 50 are provided on their lower end portions with a pair of offset fork pieces 52, 54 respectively which are slotted to slidably receive the rod 20 and are spaced from the respective brackets 48, 50, as will be clearly understood.

Needless to say, by virtue of the slots 16 and the flat end portions 18 of the rod 20, the rod is freely slidable but non-rotatable in the member 12, and a pair of pendulum-shaped release actuating elements 56, 58 are swingably suspended from the rod 20, as will be presently described.

The elements 56, 58 are configurated as is best shown in Figure 5 and are provided with an opening 60 so that they may be slid into position on the rod 20 over the flat ends 18, the element 56 being disposed between the bracket 48 and the fork plate 52, while the element 58 is similarly disposed between the bracket 50 and the fork plate 54.

By virtue of this arrangement the elements 56, 58 may oscillate in response to forward or backward "jerking" of the railroad car, and in addition, the rod 20 may be slid to one side or the other without the elements 56, 58 sliding therewith.

The elements 56, 58 are preferably provided with weights 62 so that the inertia thereof is substantially increased, and it will be noted that when either of the elements is subjected to oscillation, the shoulders 64 thereof will engage and bear upwardly on the underside of the aforementioned bars 44, thus lifting the arm 28 and disengaging either of its notches from the slot 46 in the bracket 48.

Before proceeding to describe this action further, it may be explained that the elements 56, 58 are also provided with additional openings 66 to slidably receive pointed prongs 68, 70 respectively which are secured to the flattened end portions 18 of the control rod 20 and are slidable therewith.

Having thus described the construction of the invention, the operation thereof will now be explained.

Assuming the bleeder valve 82 to be closed and the mechanism in the position shown in Figures 1 and 2, the prongs 68, 70 are extended through the openings 66 of the respective elements 56, 58 so that oscillation of these elements on the rod 20 is prevented while the railroad car is travelling.

However, when it is desired to bleed the brakes, one of the handles 24 may be pulled so as to slide the rod 20, for example, in the direction of the

arrow 72 in Figures 1 and 2, until the notch 36 enters the slot 46 and the prong 68 is disengaged from the element 58, as shown in Figure 3. The sliding of the rod 20 will, of course, open the bleeder valve 82 and the bleeding operation will be effectively performed without the necessity of the operator holding the appropriate handle (24) in its outwardly pulled position.

Thereupon, as soon as the railroad car is "jerked" such as for example, by shunting, the element 58 will oscillate and the shoulders 64 thereof will engage the bars 44, thus lifting the locking arm 28 and disengaging the notch 36 from the slot 46. This action, in turn, will permit the rod 20 to return to its normal, central position so as to close the bleeder valve 82, it being understood that the bleeder valve mechanism usually embodies in its construction means for automatically returning the rod 20 to its central position as soon as outward pulling force thereon ceases to be exerted.

The bleeding operation may be effected from either side of the railroad car, such as for example, by pulling the remaining handle (24) so as to slide the rod 20 in the direction of the arrow 74. In the latter instance, the notch 34 will enter the slot 46 and the element 56 will be free to oscillate while the element 58 is locked against oscillation by the prong 68. In either event, the result is the same, the two handles 24 and the two elements 56, 58 being provided so as to facilitate performance of the bleeding operation from either side of the car.

To assist in returning the rod 20 to its central position wherein the bleeder valve 82 is closed, a coil spring 76 may be positioned on the rod between a collar 78 and a keeper 80. The collar 78 is secured to the rod 20 and one end of the spring 76 is secured to this collar, while the keeper 80 is secured to the bracket 48 and the last coil of the spring is anchored in the keeper, so that sliding of the rod in one direction (see arrow 72) will compress the spring, while sliding of the rod in a relatively opposite direction (see arrow 74) will cause the spring to be stretched. The spring is, in effect, "double acting" insofar that it tends to assume its partly stretched, partly compressed position, wherein the rod 20 is centrally disposed and the bleeder valve is closed. Therefore, sliding of the rod 20 in either direction will place the spring 76 under strain, whereby the rod will be urged back to its central position as soon as the arm 28 is lifted by either of the elements 56, 58.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a air brake bleeding mechanism for railroad cars, the combination of a control rod slidably from a closed bleeder to an open bleeder position, a stationary catch, a locking arm pivoted to and slidably with said rod, said arm being provided with a detent engageable with said catch when said rod is in the open position, a lifting

member secured to said arm, and a release actuating element pivotally mounted for oscillation in response to movement of a railroad car on which said apparatus is provided, said element being engageable with said lifting member to disengage the detent on said arm from said catch.

2. The device as defined in claim 1 together with resilient means for urging said rod to the closed position.

3. The device as defined in claim 1 wherein said element is pivotally mounted on said rod.

4. The device as defined in claim 1 together with means for automatically locking said element against oscillation when said rod is in the closed position.

5. In an air brake bleeding mechanism for railroad cars, the combination of a control rod slideable from a closed bleeder position selectively in opposite directions to respective open bleeder positions, a locking arm pivoted to and slideable with said rod, a stationary catch, said arm being provided with a pair of detents selectively and individually engageable with said catch when said rod is in the respective open positions, a lifting member secured to said arm, a pair of release actuating elements pivotally mounted for oscillation in response to movement of a railroad car on which said apparatus is provided, said ele-

ments being selectively and individually engageable with said lifting member to disengage the respective detents from said catch, and automatic means for locking both elements against oscillation when said rod is in the closed position and for selectively and individually locking said elements against oscillation when the rod is in the respective open position.

6. The device as defined in claim 5 wherein said means comprise a pair of longitudinally spaced prongs parallel to said rod, said release actuating elements being provided with openings to slidably receive the respective prongs when the control rod is in its closed position, whereby said elements may be selectively and individually shifted to a position wherein they may oscillate in the space between the prongs when the control rod is slid to its respective open positions.
